UNITED STATES PATENT OFFICE.

WESLEY J. RHEINFRANK, OF CHICAGO, ILLINOIS.

TOY TURBINE.

Application filed November 6, 1924. Serial No. 748,010.

To all whom it may concern:

Be it known that I, WESLEY J. RHEINFRANK, a citizen of the United States, residing at Chicago, in the county of Cook 5 and State of Illinois, have invented new and useful Improvements in Toy Turbines, of which the following is a full, clear, concise, and exact description, reference being had to the accompanying drawing, forming 10 a part of this specification.

My invention relates to toy turbines and it has particular reference to that class of toys which afford not only pleasure but also 15 serve to improve the mind of the child by reason of their practical value from the standpoint of educational activity. This invention consists of means for providing the child with an opportunity to observe the operation of a toy turbine and give consideration thereto, thereby presenting a 20 variety of purposeful, educational, practical and useful objects which the outwardly observable facts gleaned from the mere mechanical toys in common use never accord 25 to the child.

One of the objects of my present invention is to provide a toy which is simple in its construction, easily and readily assembled and inexpensive to manufacture.

Another object of my invention is to provide a toy which in addition to being pleasing entertainment for a child is useful and helpful from an educational standpoint.

Another object of my invention is to provide a toy turbine which will take a predominant part in the play of the child in that, by reason of the power derived from my toy turbine, the child is able to propel and operate his other mechanical toys.

Another object of my invention is to provide water buckets for a rotor wheel in a toy turbine which are integrally formed upon the rotor and which, by reason of such construction, possess durability and reliability.

Further objects of my invention will appear from the detailed description of my invention and the appended claims.

By reason of my invention, I may provide the child with a toy which is inexpensive and safe to operate. The toy of my invention is capable of performing in the same manner as an electric motor and functions quite as satisfactorily. My present invention utilizes water power as its energy and is so constructed and adapted that it

transmits power in much the same manner as an electric motor, that is, by means of a belt which may be easily and rapidly attached to a driving pulley with which I have 60 provided my toy turbine.

Further, I utilize a method in constructing my toy turbine that obviates the necessity of frequent inspection of the inner construction of my toy. I form the water buckets integrally with the rotor, thus making 65 them permanently attached thereto and incapable of being jarred loose, removed or otherwise loosened or detached.

For a better understanding of my invention reference may be had to the accompanying drawing in which:

Figure 1 is a side elevational view of a toy turbine embodying one form of my invention, with the lower portion of the turbine casing broken away;

Fig. 2 is a cross-sectional view of my toy turbine taken on the line 2-2 of Fig. 1;

Fig. 3 is a view showing a sheet metal section constituting the rotor immediately 80 prior to its being formed and bent to provide water buckets; and

Fig. 4 is a view of the same portion, with two completed buckets and one bucket to be bent and formed as the others.

A casing 1 encloses a rotor wheel 4 to which buckets 2 are attached. The buckets are adapted to receive the water stream directed upon the toy turbine thereby revolving and propelling the rotor wheel 4. The casing 1 is supported upon legs 6 which are affixed to a base 7. The casing 1 comprises an upper portion 1^a and a lower portion 1^b and is made water tight by securing these two portions together through the medium of flanges 16. A vent pipe 12, having openings at 13 enters the lower portion 1^b of the casing and below the vent pipe 12, a nozzle 10 likewise enters this casing. At 11 the nozzle 10 may be attached to a rubber hose 95 or other suitable means for conducting water to the nozzle 10 from a water faucet. At the lowest portion of the casing is an exhaust pipe 9 with its opening at 8 which serves to remove the deenergized water from the casing 1. A shaft 14 is secured to the rotor wheel 4 and attached thereto by means of attaching and supporting members 15. The shaft 14 is rotatably mounted upon 100 bearings 17 and, at one end of the shaft 14, a driving pulley 3 is attached.

Referring now to the construction of the

rotor wheel 4 and its buckets 2, said rotor wheel 4 is stamped in circular form from a piece of sheet metal.

In Figs. 3 and 4 I have illustrated the method of forming the rotor buckets 2. The sheet metal circular form is radially slotted at spaced points as shown by slots 18 and 20. Circumferential slots 19 are formed which are spaced a short distance from the outer periphery of the rotor. The slots 19 are bisected by the radial slots 18 and the radial slots 20 and are spaced from one another substantially as shown. The sheet metal is then bent upwardly along the lines 23 and 25 adjacent respectively to the slots 18 and 20. It will be noted that the lines 23 and 25 are discontinued where they intersect the circumferential slots 19. These portions constitute the two sides of the rotor bucket 2. The metal between the slots 18 and 20 is then bent circumferentially along the line 24 which is intersected at each of its ends by the adjacent slots 19. This portion of the metal constitutes the lip of the bucket. The portions 26 and 27 of the metal that are adjacent to the outer periphery of the rotor are bent back as shown in Fig. 4 and serve as reenforcing means for the lip 24 of the bucket. The portions 26 and 27 may, if desired, be welded or soldered to the corresponding side portions of the bucket. When the bucket assumes the shape as shown by the bucket 2^a of Fig. 4 it is then twisted so that the plane of the bucket is perpendicular to the plane of the rotor as shown by the buckets 2^b and 2^c of Fig. 4. From the foregoing it is to be noted that the buckets are integrally formed upon the rotor 4 and through a very simple manipulation of the sheet metal constituting the rotor.

While I have shown and described one embodiment of my invention it is to be understood that many modifications can be made therein without departing from the spirit and scope of the appended claims.

Having thus described my invention, what I claim as new and desire to secure by Letters Patent of the U. S. is:

1. A toy turbine comprising a rotor, and buckets therefor, said rotor being stamped from a piece of sheet metal in the form of a circle which is radially slotted and circumferentially slotted at the tip of the buckets for the purpose of bending and forming said slotted portions into said rotor buckets, the

metal adjacent to said circumferential slots being bent to form sides and lips for the rotor buckets.

2. A toy turbine comprising a rotor formed from a circular metal sheet that is radially and circumferentially slotted at spaced points adjacent to the periphery, the metal adjacent to the radial slots being bent upwardly to constitute the sides of the rotor bucket and the metal intermediate the radial slots and adjacent the circumferential slots being bent upwardly to form the lip of the rotor buckets, and the metal between the bent portions then being bent in a plane perpendicular to the plane of the rotor thereby forming a rotor bucket.

3. A one piece rotor comprising a plurality of peripherally disposed scoop-shaped buckets having their planes coaxially and perpendicularly arranged, said buckets being formed at spaced radial slots and spaced intercepting circumferential slots in a sheet metal disk.

4. A one piece rotor comprising a plurality of peripherally disposed scoop-shaped buckets having their planes coaxially arranged, said buckets being formed by circumferentially and radially slotting a disk member at spaced points, the sides of the buckets being formed at said radial slots and being intercepted by the circumferential slots and the lips of the buckets coinciding with said circumferential slots.

5. A one piece rotor comprising a plurality of peripherally disposed scoop-shaped buckets having their planes coaxially arranged, said buckets being formed by circumferentially and radially slotting a disk member at spaced intervals and bending and twisting said slotted segments so that the planes thereof are perpendicular to the circumference of said disk member.

6. A one piece rotor comprising a plurality of peripherally disposed scoop-shaped buckets having their planes coaxially arranged, said buckets being formed by stamping spaced circumferential slots adjacent the periphery of a disk member, and by stamping radial slots which bisect each of said spaced circumferential slots and bending such slotted portions of said disk member into substantially scoop-shaped members.

In witness whereof, I have hereunto subscribed my name.

WESLEY J. RHEINFRANK.
